UNITED STATES PATENT OFFICE.

ALFRED EILERT, OF ST. LOUIS, MISSOURI.

PRESSING MACHINE.

Application filed July 12, 1924. Serial No. 725,546.

To all whom it may concern:

Be it known that I, ALFRED EILERT, a citizen of the German Republic, residing at St. Louis, Missouri, U. S. A., have invented

5 a certain new and useful Improvement in Pressing Machines, of which the following is a specification, such as will enable others skilled in the art to which it appertains to make and use the same.

10 My invention relates to new and useful improvements in pressing or ironing machines, and the objects of the invention are to provide a pressing machine having a plurality of work supporting forms or boards, 15 said boards being of various shapes and sizes for receiving various garments and parts thereof.

Further objects of the invention are to provide a pressing machine having a plurality of interchangeable supports or boards which can be easily placed in operating position and can be readily brought into cooperating engagement with the iron which is adapted to receive reciprocating motion.

25 Still further objects of the invention are to generally improve upon and simplify the construction of the pressing machines and provide suitable mechanism for controlling and actuating the same.

30 With these and other objects in view, my invention consists in certain novel features of construction and arrangement of parts, hereinafter more fully described and claimed, and illustrated in the accompanying drawings, in which—

Figure 1 is a top plan view of a pressing machine.

Figure 2 is a front elevational view of the same.

40 Figure 3 is a vertical cross section taken transversely through the machine.

Figure 4 is a vertical cross section of the iron and the board and showing the latter in cooperating position with said iron.

45 Figure 5 is a detail view of the operating mechanism of the machine.

Figure 6 is an enlarged cross section taken through one end of the machine.

50 Figure 7 is a perspective detail view of one of the ironing boards designed to be used in connection with pressing pleats.

Figures 8 to 10 are plan views of various interchangeable ironing boards.

55 Figure 11 is a cross sectional detail view illustrating means for supporting the removable boards in position on the machine.

Figure 12 is a detail view showing means for maintaining the board supporting member in operative position.

Referring by numerals to the accompanying drawings, 10 indicates the side frame members connected by a rear frame member 11 and a front cross member 12. The side frames 10 are provided with vertically disposed slots 14 in which are mounted for vertical movement bearing blocks 15 receiving trunnions 16 of a revolute member 17. This revolute member has a polygonal peripheral surface and is preferably triangular in cross section, thereby providing a series of tables or work benches 18^a and 18^b and 18^c, as shown in Figure 3 which support an ironing board 19, a shoulder lining ironing board 20, and a pleated goods ironing board 21, respectively. Ironing board 19 is supported on the bench 18^a by a removable bracket 19^a while board 20 is detachably held in position on the bench 18^b by a leg 20^a which is non-circular in cross section and fits in a socket 20^b secured to bench 18^b. A series of 60 these boards 20 is provided and they are formed of various shapes and sizes in order to enable the operator to select the proper board for ironing shoulder linings and other portions of various garments. Ironing board 21 is also provided with a depending leg 21^a which fits in a non-circular socket member carried by the bench 18^c and detachably supports said board thereon. Boards 21 are used in connection with ironing pleated material, such as skirts. In 65 pressing pleated material, the fold of the upper or overlapping pleat leaves a line or mark on the lower pleat and it is necessary to press each pleat separately, after pressing 70 the garment, in order to remove this line or mark. Boards 21 are provided in various widths in order to permit ironing pleats of various sizes.

To prevent displacement of the board, the legs thereof can be locked in the socket members in any suitable manner, such as by means of a thumb screw 22 shown in Figure 11.

An iron 24 heated in any suitable manner, preferably by gas, supplied by connection 24^a, is disposed a suitable distance above revolute member 17 and is adapted to be engaged by one of the ironing boards, which, when member 17 is raised, presses against 105 the lower face of said iron. This iron 24 is supported by the downwardly curved ends 110

- of arms 25 which have their opposite ends secured to a horizontally disposed bar 26 slidably arranged in bearings 27 which are fixed to rear frame member 14. Bar 26 receives reciprocating motion through a crank arm 28 connected to said bar by a link 29 and fixed to a shaft 30 which is operated by motor 31 through suitable reduction gearing 32.
- 10 When the machine is in operation, iron 24 is constantly moved back and forth over the garment pressed thereagainst by one of the boards and thus the garment is ironed in an efficient and economical manner. A cross bar 34 is secured at its ends to extensions of side frame members 10 and provides sliding support for members 35 carried by arms 25.
- 15 Means for raising member 17 into operating or pressing position comprises a foot board or pedal 36 secured to the outer ends of levers 37 which are pivotally mounted at 38 in the side frames 10 and have their inner ends pivotally connected to the lower ends of links 39, the upper ends of which are pivotally connected to extensions depending from bearing blocks 15. When pedal 36 is depressed, the inner ends of levers 37 are raised and causes member 17 to move upwardly, whereby one of the ironing boards is pressed against the longitudinally movable iron 24. The degree of pressure with which the ironing board is held against iron 24 can be regulated by increasing or decreasing the pressure applied to the foot board 36. Counter-balance weights 40 are suspended adjacent to each side frame member from one of the ends of cables 41 which extend upwardly and pass over pulleys 42 secured to the side frames and then extend downwardly and have their opposite ends attached to lugs formed on the ends of levers 37, thereby balancing said member 17 and facilitating the movement thereof in a vertical plane.
- 20 The various ironing boards are spaced or raised from their respective tables the usual distance in order to provide sufficient clearance for properly arranging the garment in position on the board. Therefore, it is necessary to space supporting members 17 a suitable distance from the rear frame member 11 in order to provide suitable clearance for said ironing boards when member 17 is rotated to place the proper ironing board in operative position. To prevent the garments from entering this space, and also to exclude dust and other foreign material from passing downwardly, a shelf 44 is arranged rearwardly of member 17 and in a horizontal plane with the upper face or working table thereof. This shelf is pivotally supported at its ends by brackets 43 which extend rearwardly and upwardly from bearing blocks 15 so that when the member 17 is raised, shelf 44 moves with it and is therefore maintained in proper position relative to the respective work bench table of member 17. When member 17 is rotated so as to position a different ironing board for cooperation with the iron, said shelf is tilted upwardly so as to permit the respective board to traverse the space between member 17 and the rear frame element. In order to provide an automatic opening or tilting of shelf 44, a cam 45, having three depressions arranged in its periphery in a predetermined relation with the tables of member 17, is provided and operates with a roller 46 carried by an arm 47, which latter is pivotally mounted on bracket 43. This arm is connected by a link 48 to a depending arm 44a of shelf 44 whereby, when roller 46 enters one of the depressions on cam 45, arm 47 is moved rearwardly by a spring 49 and causes shelf 44 through its interengagement with link 48 to be rocked upwardly out of the path of movement of one of the ironing boards when the member 17 is rotated. Cam 45 occupies a fixed relation relative to member 17 and is arranged so as to actuate arm 47 in proper timed relation with the movement of the various ironing boards so that shelf 44 is lifted and moved out of the way of the respective boards at the appropriate time.
- 25 The centering and locking means for member 17 comprise a three-way cam 50 fixed to one of trunnions 16 and having its periphery engaged by a pressure foot or roller 51 carried by a plunger 52. This plunger is slidably mounted in a sleeve 54 and is yieldably forced against said cam by a spring 55 arranged in said sleeve. Sleeve 54 is carried by and fixed to one of the bearing blocks 15 and consequently occupies a fixed relation with respect to member 17 and its work tables.
- 30 The pressure exerted by the spring pressed plunger against cam 50 is sufficient to prevent accidental rotation of member 17 and also serves as a brake for preventing over rotation of said member 17.
- 35 The disposition of the three pockets or depressions on cam 50 is such that when one of the pockets is in alignment with roller 51, the respective table occupies proper working position.
- 40 The lower ends of slots 14 are preferably provided with pockets 56 in which are disposed comparatively small coiled springs 57 which, when member 17 is restored to its downward position, are adapted to be engaged by bearing blocks 15 and act as shock absorbers and eliminate jarring of the machine and prevent damage thereto.
- 45 A pressing machine constructed according to my invention is highly efficient in operation, is particularly well adapted for use in ironing various articles without ne-

cessitating changes or adjustments of the machine and is so arranged that it can be operated and controlled without manipulation by the operator, thereby leaving his hands free for adjusting and operating upon the article to be ironed.

While I have shown and described the preferred form of my pressing machine, it is obvious that various changes in the construction and arrangement of parts of my improved machine can be made and substituted for those herein disclosed, without departing from the spirit of my invention.

15 I claim:

1. A pressing machine comprising in combination a longitudinally movable iron, bearings mounted for vertical movement, and a polygonal member having its trunnions journaled in said bearings, there being a plurality of ironing boards supported on said member, the latter being rotatable to position any one of said boards in cooperative relation with said iron, said member being movable in a vertical plane for bringing one of said boards in pressure engagement with said iron.

2. A pressing machine comprising in combination a horizontally movable iron, a vertically movable and revoluble member provided with a plurality of ironing boards and movable to position any one of said boards in cooperative engagement with said iron, means for counterbalancing said member, and an actuating member for controlling said board supporting member and regulating the pressure with which said boards are applied to said iron.

3. A pressing machine comprising in combination an iron, stationary supports, vertically movable bearings mounted therein, a revoluble member journaled in said bearings, ironing boards circumferentially arranged on said member, said member being adapted to be actuated to position any one of said boards in cooperative relation with said iron, and automatic means for centering and locking said member in cooperative position.

50 4. A pressing and ironing machine comprising in combination a downwardly facing iron, journal boxes mounted for vertical movement, a polygonal member rotatably journaled in said boxes, a plurality of interchangeable ironing boards carried by said polygonal member and movable therewith into operative engagement with said iron, means for retaining said polygonal member in any of the operative positions, and a pedal for raising said polygonal member and bringing the positioned board into pressure engagement with said iron.

55 5. An ironing machine comprising an iron adapted to be heated, a member having a plurality of work tables arranged

circumferentially thereto and operable to position any one of said tables in cooperative relation with said iron, an ironing board supported on each table, connections operable to raise said member and bring the positioned board into engagement with said iron, and an extension shelf arranged rearwardly of and in horizontal plane with the positioned table and movable in a vertical plane therewith.

6. An ironing machine comprising an iron, a member having a plurality of work tables circumferentially disposed thereon and operable to position any one of said tables in cooperative relation with said iron, an ironing board supported on each table, connections operable to raise said member and bring the positioned board into engagement with said iron, an extension shelf arranged rearwardly of and in a horizontal plane with the positioned table of said member, and mechanism operable in correlation with said supporting member for displacing said shelf and allowing the ironing boards to pass when said member is being adjusted.

7. An ironing machine comprising in combination a frame, upwardly extending arms slidably supported by said frame, a downwardly presented iron carried by said arms, bearing blocks mounted for vertical movement in said frame, a polygonal member having its ends rotatably journaled in said blocks and being provided with a series of circumferentially disposed work tables, an ironing board supported on each work table and adapted to cooperate with said iron, automatically operable retaining means for said member for maintaining any one of said work tables in operating position, and operating means for actuating said member in a vertical plane whereby one of the ironing boards is brought into pressing engagement with said iron.

8. An ironing machine comprising a frame, arms slidably supported by said frame and having upwardly extending upper ends, a downwardly facing iron carried by the upper ends of said iron, bearing blocks mounted for vertical movement in said frame, a member journaled in said blocks and provided with a plurality of circumferentially disposed work tables, an ironing board arranged on each table and adapted when said member is rotated to be brought into cooperative relation with said iron, means for centering and locking said member in predetermined positions, a pedal for actuating said board supporting member whereby the selected board is brought into pressing engagement with said iron, and weights for counterbalancing said member.

9. In a device of the class described, the combination with an iron, of a revoluble member provided on its periphery with a

1. plurality of work tables, ironing boards removably supported on said tables, said member being adjustable to bring any one of said boards in a vertical plane with said iron, means for raising said member and thereby bringing the positioned board in pressure engagement with said iron, and weights for counterbalancing said member.

10. In an ironing machine, the combination of a stationary support including side frames provided with aligned vertically disposed slots, bearing blocks movably disposed in said slots, a work table disposed between said side frames and rotatably supported by said bearing blocks, said table being triangular in cross section to

provide a plurality of working surfaces, an ironing board arranged on each face of said table, an iron movable longitudinally and held against movement in a vertical plane, 20 treadle operated mechanism for operating said blocks and raising said table so as to bring the corresponding ironing board in pressure engagement with said iron, said table being rotatable so as to selectively 25 bring any one of said boards in operative position, and means for retaining said table in its selected position.

In testimony whereof I hereunto affix my signature this 28th day of June, 1924.

ALFRED EILERT.
